HORN

Richard Felgner, Springfield, Long Island, N. Y.,
assignor to T. Cohn, Inc., Brooklyn, N. Y.

Application November 30, 1938, Serial No. 243,129

7 Claims. (Cl. 46—180)

This invention concerns a horn, and more particularly a wind instrument in which a reed is interposed in a passage or superimposed upon end or side openings of a wind channel.

For various reasons it is ordinarily not desirable to execute the reed in one with the support, i. e. integrally with the surrounding parts. Therefore we frequently find the reeds to be riveted, wedged, screwed, clamped, or frictionally mounted in place. In other cases an adhesive or solder is used, care being exercised in all instances to arrange the reed permanently and cleanly, so that the tonal quality of the reed or reed material is not impaired.

In the instant invention the reed is mounted by electric welding, and more particularly by way of the Thompson or resistance welding process. Such a practice can be carried out most economically, and—contrary to the concepts of the prior art,—a high tonal quality may be obtained, if the reed is properly mounted or is preconditioned for a proper mounting. In a spot or seam weld, as they come into question in the instant invention, the actual juncture between the joint materials is extremely limited in area in comparison with a reed mounted upon a support by other fastening methods. Thus a spot weld interconnecting a reed with a support will normally be surrounded upon all sides by an area at which the parts have not been united, and at which they may not even be in abutment with each other.

When a reed is mounted by way of spot welding, the parts of the reed to the sides and to the back of the spot weld will therefore be subject to vibrations just like the reed proper i. e. the tongue, which is the sound element proper. Thus it would be impossible to obtain a clear tone, if a flat reed of the prior art were assembled in an instrument by way of spot-welding.

Such a disadvantage of a spot welded reed has been overcome in the instant invention by curving, kinking, bending or denting the rear parts of the reed in such a manner, that obnoxious vibrations are modulated, damped, or completely avoided, as it may be desired.

Such shaping of a portion of the reed has the additional advantage that a standard blank may be used for a reed and may be fully controlled as to vibrations, the curved or bent portions of the reed being enlarged or restricted accordingly.

The instant invention is herein exemplarily illustrated by way of a very simple horn, which is coiled—from a printed sheet of metal for instance—into a truncated cone. It is an added

object of this invention to secure the overlapping sides of such a piece of sheet material upon each other, in the same operation in which a reed is mounted thereon.

These and other objects of this invention, which will be better understood from the following exemplary description, will now be elucidated by way of a simple showing, which is, however, to be considered as illustrative only, and not in limitation of this invention.

In the drawing:

Fig. 1 is a top view of a blank to be converted for a reed.

Fig. 2 is a corresponding side view.

Fig. 3 shows a blank like that of Fig. 1, arched and lightly shaped for the purpose of this invention.

Fig. 4 shows a corresponding cross-sectioned side view.

Fig. 5 shows a blank of the kind shown in Fig. 1, which has been more strongly bent and shaped than the embodiment of Fig. 3 so that the portion of the reed which may vibrate, is better defined and probably shortened.

Fig. 6 shows a corresponding cross-sectioned side view.

Fig. 7 shows a partly sectioned side view of a horn in which, for instance, a reed of the kind shown in Fig. 3 is used.

Fig. 8 is a fragmentary, partly cross-sectioned side view, which serves to illustrate how the welding operation is performed.

Fig. 9 shows a top view of the parts of the horn of Fig. 8 after they have been welded.

Fig. 10 is a corresponding end view.

Similar numerals refer to similar parts throughout the various views.

Fig. 7 of the drawing shows a simple form of a horn, in connection with which the instant invention is to be described. The tube 11 is shown to be coiled up from a substantially trapezoidal blank of sheet metal into the shape of a truncated cone. The overlapping sides 12 and 13 of the sheet metal may be suitably united. They will here be shown to be united by the spot weld 14, by which the reed 15a is also assembled with the tube 11. The vibratory portion or tongue 16 of the reed extends free to the right, and substantially registers with the slanted top opening 17 of tube 11. A mouth piece, e. g. the wooden nipple 18, is assembled with the tube 11, being engaged, for instance, upon the tapered circumference of the tube above reed 15a by way of a push fit. The horn is actuated and used by engaging the free end of nipple 18 in the mouth and blow-

ing thereinto. The tongue 16a of reed 15a is caused to vibrate, and these vibrations contribute in determining the length of the sound waves propelled from the large end of tube 11.

5. A flat reed blank 15 is shown in Figs. 1 and 2. The portion 19 to the left is to be converted as a base, whereas the portion 16 to the right serves as a vibrating tongue.

According to this invention the base 19 of reed 15 is curved transversely to the direction at which the tongue 16 extends therefrom. Thus we limit the portion of the tongue which is not curved in the said direction, and which is therefore free to vibrate. When the tongue 16 is to remain free and as large as possible, little curvature is applied to the base 19a. It is for instance shaped cylindrically or conically, as indicated at 19a in connection with the reed 15a of Figs. 3 and 4. It will be noticed that such curvature merging with the flat portion of the tongue 16a produces a reenforced cross-section of transition, which effectively dampens or interferes completely with any propagation of the vibrations of the tongue 16a to the left, towards the base 19a. The radius of the transverse curvature is preferably adjusted to be slightly less than the radius of curvature of the tube 11, where the reed is to be attached thereto. Thus the base 19a, and more particularly its sides, are forced into firm and stable abutment upon the tube, when the base 15a is welded onto the tube 11 by way of a central spot weld 14. Reinforcing edges may be introduced into the curved surface of the base 19; e. g. an inclined flat cross-formation 20 may be struck up therein, as shown in connection with the reed 15b of Figs. 5 and 6. Such an arrangement imparts positive convexity to the base 19, and will also serve to delimit the tongue 16b more sharply, if so desired, as shown in the said Figures 5 and 6.

An arrangement for performing the welding operation is shown in Fig. 8. The tube 11 is slid into abutment onto a substantially horizontal electrode 21 of a spot-welding apparatus, into a position in which the overlapping edges 12 and 13 substantially underlie the vertically reciprocatable second electrode 22 of such apparatus. Onto the overlapping seams of the tube 11 thus mounted upon the electrode 21, is fed a reed 15b so that the base 19b overlies the overlapping seams 12 and 13 and so that the tongue 16b substantially registers with the opening 17 at the top end of tube 11. Before the spot welding operation is carried out, the reed 15b may be retained in this position by an arm 23, which depresses the reed 15b into the registering position, engaging for instance centrally upon the cross-formation 20. The spot welding operation is now performed by lowering the second electrode 22 and passing currents therefrom through the overlying three layers 19b, 12 and 13 to the first electrode 21. The arm 23 and the electrode 22 may then be released, and the spot-welding operation is finished.

A party versed in the metal working arts will understand that a die, which produces the deformation of the reed, shown in Figs. 5 and 6, in connection with reed 16b, may also produce the deformation 16a of Figs. 3 and 4, by a simple adjustment in the die, or even by merely striking the reed 16 less hard than it would be necessary in producing the reed 16b. The deformation of the reed may be enhanced, and additional adjustment may be brought about as to its curvature, if the arm or holder 23 is advanced so far onto the cross-formation 20, or onto the corresponding portions of the reed 16a, that the reed is indented thereby. Such an indenture 24 is for instance indicated upon the reed 15b in Fig. 9. 15

Having thus described my invention in detail I do not wish to be limited thereby, except as the state of the art and the appended claims may require, for it is obvious that various modifications and changes may be made in the form of embodiment of my invention, without departing from the spirit and scope thereof.

I claim:

1. A sound instrument comprising a tube and a reed, said reed having a transversely curved base resistance welded onto said tube and a flat tongue extending over an opening in said tube. 25

2. A sound instrument comprising a conical tube and a reed, said reed having a transversely curved base spot welded onto said tube and a flat tongue extending over an opening in said tube. 30

3. A sound instrument comprising a tube, and a reed, said reed having a base resistance welded onto said tube and a flat tongue extending over an opening in said tube said base being convexly shaped and merging at a curved line with said tongue in order to limit the vibrations of said reed. 35

4. A sound instrument comprising a tube and a reed, said reed having a base resistance welded onto said tube and a flat tongue extending over and adapted to close an opening in said tube, said base being curved in order to fit in abutment onto said tube and to limit the vibrations of said reed. 40

5. A sound instrument comprising a tube and a reed, said reed having a base resistance welded onto said tube and a flat tongue extending over an opening in said tube said base being convexly shaped and indented in order to limit the vibrations of said reed. 45

6. A sound instrument comprising a tube having overlapping edges, and a reed having a curved base assembled with said tube by a resistance weld across the overlapping edges of the tube and a flat tongue extending over an opening in said tube. 50

7. A sound instrument comprising a tube and a reed, said reed having a base resistance welded onto said tube and a flat tongue extending over an opening in said tube, said base having irregularly struck-up portions producing transverse reinforcing ridges therein. 55

RICHARD FELGNER.
